WATER COOLER

John Carl Wichmann, Beverly Hills, Calif.

Application January 28, 1932. Serial No. 589,416

23 Claims. (Cl. 62—91)

My invention relates to a water cooler of a type in which water in a bottle or similar receptacle may be cooled by an air draft, such draft increasing the evaporation of moisture adjacent the exterior of the bottle or receptacle.

My invention pertains particularly to the type of water cooler used in connection with the sale and use of bottled water in which the bottle in which the water is vended is inverted over a receptacle which becomes filled with the water from the bottle, and the water in such receptacle is cooled for drinking purposes.

In connection with such a device I provide an absorbent medium on the outside of the water receptacle and maintain this moistened by a slight flow of water from the inside of the receptacle to the absorbent cover on the outside. A cover or case surrounds the receptacle and extends from the bottom to the top, and through the space between the case and the receptacle I blow a current of air, which air current increases the evaporation of the moisture from the absorbent cover and, hence, increases the cooling effect on the water in the receptacle. In this connection a feature of my invention is the construction of a stand with an annular trough having a rim and a supporting base inside of the trough, on which base is mounted the water receptacle. This water receptacle is open at the top and has a rubber pad or ring to support the inverted bottle of water. The receptacle is provided with an absorbent cover which may extend slightly into the trough. The water is fed from the inside of the receptacle through a glass siphon tube which passes through an opening in the receptacle from the inside to the outside, which siphon tube is provided with a wick or other medium for allowing a flow of water by capillary attraction. This may be of a construction set forth in my patent application Ser. No. 571,897, filed Oct. 29, 1931, for a Radium emanator and water filter.

The base is hollow and is provided with an upstanding rim, on which rim is supported the container or case, there being a series of perforations through the rim connecting between the hollow base and the space between the case or container and the receptacle. The opening at the top of the case or container allows for the circulation of air, which circulation is devised preferably by an electric motor operating a fan connected to the hollow base. An overflow is provided from the trough to a waste receptacle.

My invention is illustrated in connection with the accompanying drawing, in which:

The figure is a vertical section showing my water cooler with the associated elements.

In my construction I employ a supporting base 11 which is illustrated as having a flat bottom 12, a cylindrical side wall 13, a top supporting wall 14, an annular trough 15, a hollow rim 16, which rim has an annular groove 17. The upper and inside edge of the rim is provided with a series of perforations 18. This base has a strengthening bead 19 on the outside and below this bead there are the attachment means 20 for the legs 21 which support the hollow base above the floor. The base has the hollow chamber 22.

The water receptacle 23 is preferably cylindrical with a circular bottom and usually made of glass and is supported on the supporting base 14. It has a contracted neck 24 at the top in which is fitted a rubber ring 25 and on this ring is supported the inverted bottle 26. A case or container 27 has a lower annular edge 28 which fits in the annular groove 17 on the rim of the hollow base. The case has an inward curve 29 at the top and is provided with an annular opening 30. This opening leaves an annular opening at the top of the receptacle.

The outside of the receptacle is provided with an absorbent cover 31, the lower portion 32 of this cover extending below the supporting base 14 into the trough 15. A glass siphon tube 33 is fitted in a rubber or similar packing 34, which latter is tightly wedged in an opening 35 in the receptacle. This tube has an inner portion 36 and an outer portion 37. A wick 38 is packed in the tube and the inside end portion 39 extends below the tube to be always immersed in the water inside the receptacle. The outer end 40 of the wick preferably extends below the outside end of the tube and is caught underneath the cover 31 of the receptacle. The water is drawn from the receptacle by means of the faucet 41, which leads from the receptacle through the cover 31 and through the lower portion of the case 27. In order to cause an air circulation I provide a fan or air blower 42 which may be of any suitable type. This shows a pipe 43 leading from the fan or blower to the hollow base 11 and an air connection 44. The fan or blower is driven by an electric motor 45, the motor and fan being mounted on a bracket 46 secured to one of the legs 21.

A waste water pipe 47 extends upwardly through the hollow base and is connected to the trough 15 some place above the bottom of the trough indicated at 48. It has a discharge end 49 which

discharges into a waste water receptacle or container 50, this being suitably supported by the legs. Another waste water cup 51 receives the waste water from the faucet and carries this by means of a tube 52 to the waste water receptacle 50. In order to assure that the case or container 27 will not be tapped out of position I provide a hold-down fastening designated 53 which employs a series of screws 54 extending 10 through lugs 55 on the lower part of the case or container and threaded into lugs 56 on the strengthening bead 19.

As long as there is a supply of water in the water receptacle 23 the wick causes a transference of water to the absorbent cover 31 on the outside. When the receptacle is full this action may be started by a siphoning action. The tube 33 is fitted tightly by the packing in the opening in the receptacle; therefore, the water can only 15 pass through the tube. The flow must be relatively slow on account of the tube being filled with the wick. It is obvious that the air circulation caused by the pump may be in either direction, that is, it may be a down flow of air 20 over the absorbent medium on the outside of the water receptacle or it may be an up draft. I prefer to use an up draft as this blows the dampened, moistened air out of the opening 30 at the top, thereby giving a cooling action as 25 well as as a humidifying action to the room in which the cooler is installed. This is an important secondary characteristic in my invention especially in the summer time when the water coolers are more in demand than at other 30 seasons of the year, as the device not only functions as a water cooler but also as a humidifier and cooler of the air of the room.

While my invention is principally designed as a water cooler in which an air circulation is 40 forced over a moist surface of the water receptacle or container, it will be apparent that due to the evaporation of moisture from the forced current of air that my device will operate as a humidifier in a room in which the cooler is installed. Such humidifier, on evaporation of moisture, will function to lower the temperature 45 in a room.

The siphon tube is made of sufficient diameter that when the wick has been passed therethrough 50 to have sufficient capacity for flowing enough water to not only moisten the absorbent outside covering from the top but to allow some of this to drip into the annular trough 15. The wick by its capillary action will start or develop the siphon flow and so long as the water level is above 55 the inlet end of the siphon tube inside of the water receptacle the water will flow outwardly by a siphoning action rather than by a capillary action. However, when the water falls below 60 the inner end of the siphon tube, water will still be conveyed to the absorbent outside material by the capillary action of the wick.

Various changes may be made in the details of construction without departing from the spirit 65 or scope of the invention as defined by the appended claims.

I claim:

1. A water cooler comprising, in combination, 70 a stand, a water receptacle mounted thereon, an absorbent porous cover on the receptacle, means to moisten such cover by water from the receptacle, a case mounted on the stand and spaced from the cover and receptacle, such space providing a passage for the circulation of air, and a fan or blower to force air positively through

said passage in a direction counter to the natural air circulation, the means to moisten the cover comprising a wick extending into the receptacle and through an opening in such receptacle to the cover.

2. A water cooler comprising, in combination, a stand, a water receptacle mounted thereon, a porous absorbent cover for the receptacle, said stand having a trough with the cover dipping into the trough, means to supply water to the trough, a case surrounding the receptacle and the cover forming an air passage, means forming an external connection between the passage and external air for air circulation, and a fan or blower connected to positively force air through said passage.

3. A water cooler comprising, in combination, a stand having an annular trough, a water receptacle mounted in the stand and having a porous absorbent cover extending into the trough, means to supply water to the receptacle, a case mounted on the stand surrounding and spaced from the receptacle and the cover, means to supply water from the receptacle to the trough, such space forming an air passage, and a fan or blower to positively force air through said passage.

4. A water cooler as claimed in claim 3, the means to supply the water to the trough comprising a connection from inside to outside of said receptacle, the outside connection being adapted to moisten said cover and the cover to drip water into the trough.

5. A water cooler comprising a stand having an annular trough, a water receptacle mounted on the stand and having a porous absorbent cover dipping into the trough, a tube leading through the receptacle from inside to outside having a seal on the outside of the tube, an absorbent wick extending through the tube having one end for immersion in the water in the receptacle and the other end discharging at an upper portion of said cover, the surplus water being adapted to drip into the trough, means to support a covering case on the stand, said case being spaced from the receptacle and cover forming an air passage, and an air pump to give a positive air circulation through the passage between the case and the receptacle.

6. A water cooler as claimed in claim 5, said base having a hollow structure with perforations leading into the space between the case and the receptacle, the air circulating through said hollow base and through the perforations.

7. A water cooler comprising a hollow base having an annular trough with an annular rim outside of same, there being a series of perforations through the rim, the base having a central supporting wall with a water receptacle mounted on such wall, a porous absorbent cover on the receptacle, the rim of the base having a groove, a case having its lower edge mounted in said groove, the case being spaced from the receptacle forming an air passage, and an air fan or blower connected to the hollow base and adapted to cause an air circulation through the perforations and through said space.

8. A water cooler as claimed in claim 7, a tube extending through an opening in the receptacle from inside to outside and having a seal on the outside of the tube, a wick in the tube connecting from inside to the absorbent cover on the outside, such cover being adapted to dip into the trough, and an overflow for waste water from the trough.

9. In a method of cooling water in a receptacle, comprising maintaining a moist surface on the

- exterior of the receptacle by withdrawing water from the receptacle above the water level thereof by a siphoning action from inside to the outside of the receptacle, and creating a circulation of air over the moist exterior of the receptacle. 5
10. In a method of cooling water and humidifying air, comprising moistening the exterior surface of a water receptacle by withdrawing water from the inside of the receptacle to the outside by a siphoning action and creating a confined circulation of air upwardly over the moist exterior surface of the receptacle, thereby evaporating water from such moist surface, the evaporation of the water cooling the water in the 15 receptacle, and the humidified air being lowered in temperature. 10
11. An apparatus for humidifying air, comprising a water receptacle having a porous covering on its exterior surface, a siphon for withdrawing water from the interior of the receptacle to the exterior and to moisten such material with the water on the exterior, means forming an air passage exterior to the receptacle, and means to force an air draft through such 25 passage, thereby humidifying the air coming in contact with the moist covering on the receptacle. 20
12. In the method of cooling water and humidifying air comprising moistening the exterior surface of a water receptacle by withdrawing 30 water from the inside of the receptacle to the outside by a combined siphoning and capillary action thereby moistening the exterior surface of the receptacle, then evaporating water from the moist surface by blowing air upwardly over 35 the outside in a counter direction to the natural flow of air becoming chilled by contact with the moist receptacle, the evaporation of the exterior moisture being operative to cool the water in the receptacle and the air blown over the exterior of the 40 receptacle being humidified and lowered in temperature. 35
13. In the method of cooling water and humidifying air comprising moistening the exterior surface of a water receptacle by withdrawing 45 water from the inside of the receptacle to the outside by capillary action, maintaining a body of water with an exposed surface below the outside of the receptacle, blowing air over such water surface and over the exposed exterior surface 50 of the receptacle thereby cooling the air by the evaporation of water from the said water surface and cooling the water in the receptacle by the evaporation of the exterior water on the receptacle. 55
14. In the method of cooling water and humidifying air as claimed in claim 13, in addition maintaining the withdrawal of water from the receptacle by a siphoning action, the siphoning action operating at a high water level in the 60 receptacle and the capillary action at a lower water level. 65
15. An apparatus for cooling water and humidifying air comprising a water receptacle having a porous covering on its exterior surface, a capillary means for withdrawing water from the interior and flowing same on the exterior of the said receptacle, means to contain a body of water adjacent the base of the receptacle, means to force an air draft over the surface of said body of water and over the exterior surface of the receptacle thereby humidifying and cooling the air and cooling the water in the receptacle. 70
16. An apparatus for cooling water and humidifying air as claimed in claim 15, the said body of water being in the form of an annular 75
- trough, said trough being filled by drip from the exterior of the receptacle. 80
17. An apparatus for cooling water and humidifying air comprising a water receptacle having a porous cover on its exterior surface, a capillary means for withdrawing water from the interior to the exterior of said receptacle and moistening the exterior, means to confine a body of water at the base of the receptacle, and means to blow air upwardly from below the receptacle over the water so confined and over the moistened exterior of the receptacle. 85
18. An apparatus for cooling water and humidifying air as claimed in claim 17, the water confining means being in the form of an annular trough and the porous cover extending into said trough. 90
19. An apparatus for cooling water and humidifying air as claimed in claim 17, the capillary means comprising a wick, said wick extending through a siphon tube through the wall of the receptacle, said tube being adapted to siphon water when at a high level in the receptacle and the wick being adapted to convey water by capillary action when the water level is below that 100 of a siphon tube. 95
20. An apparatus for cooling water and humidifying air comprising a water receptacle having a porous cover on its exterior surface, a water confining means at the base of the receptacle, means to moisten the porous cover and to supply water to the water confining means, and means to blow air upwardly over the surface of the water in the water confining means and over the porous cover of the receptacle. 105
21. An apparatus for cooling water and humidifying air comprising a water receptacle having a porous cover on its exterior surface, an annular trough at the bottom of the receptacle, the porous cover extending into the trough, means to wet the cover, the surplus water descending into the trough, and means to blow air upwardly over the surface of the water in the trough and over the porous cover. 110
22. A water cooler comprising in combination a stand, a water receptacle mounted thereon, an absorbent porous cover on the receptacle, means to moisten such cover by water from the receptacle, a case mounted on the stand and spaced from the cover and receptacle, such space providing a passage for the circulation of air, and a fan or blower to force air positively through said passage in a direction counter to the natural air circulation, a tube extending from the interior to the exterior of the receptacle and sealed to prevent leakage outside of the tube and a wick extending through the tube, said wick being immersed in the water in the receptacle at one end and the opposite end being connected to the cover. 120
23. A water cooler comprising in combination a stand, a water receptacle mounted thereon, an absorbent porous cover on the receptacle, means to moisten such cover by water from the receptacle, a case mounted on the stand and spaced from the cover and receptacle, such space providing a passage for the circulation of air, and a fan or blower to force air positively through said passage in a direction counter to the natural air circulation, the means to moisten the cover comprising a tube sealed in an opening in the receptacle and adapted to siphon water from the receptacle to the cover. 130
